UNITED STATES PATENT OFFICE.

HUGO TUECKMANTEL, OF IRVINGTON, NEW JERSEY, ASSIGNOR TO THE R. NEUMANN HARDWARE CO., A CORPORATION OF NEW JERSEY.

ENGLISH OR SEWED-IN BAG FRAME.

1,151,838.

Specification of Letters Patent. Patented Aug. 31, 1915.

Application filed February 10, 1914. Serial No. 317,757.

To all whom it may concern:

Be it known that I, HUGO TUECKMANTEL, a citizen of the United States, residing at Irvington, in the county of Essex and State 5 of New Jersey, have invented certain new and useful Improvements in English or Sewed-In Bag Frames; and I do hereby declare the following to be a full, clear, and exact description of the invention, such as 10 will enable others skilled in the art to which it appertains to make and use the same, reference being had to the accompanying drawings, and to characters of reference marked thereon, which form a part of this specification. 15

The present invention relates, generally, to improvements in frames for traveling bags, satchels, and other bags; and, the invention has reference, more particularly, to 20 a bag-frame and novel angle-irons or brackets therefor to be used in the construction of that class of traveling bags known as "English" or "sewed-in" bags.

In the usual forms of sewed-in bags, as at 25 present manufactured, the stitching or sewing must be done by hand, because of the ordinary construction of the "English" or "sewed-in" bag-frame it is impossible to sew, by means of the ordinary sewing-machine, while in other forms of "English" or "sewed-in" bag-frames it is possible to sew by machine, except at the several points where the frames are provided with the usual angle-irons or brackets, at which points the opera- 30 tion of the sewing machine must be stopped, the leather-portions of the bag-body being blind-stitched by hand above the metal surfaces of the angle-irons or brackets at such points. Aside from the time consumed and 35

40 the additional cost of manufacture in thus blind-stitching the leather-portions of the bag-body located directly over the angle-irons or brackets, there is also great danger of striking the angle-irons or brackets by the 45 needles used in the sewing-machine, thus very often breaking off the needles, and also damaging the leather, as well as rendering the sewing-machine inoperative.

50 My present invention, therefore, has for its principal object to provide an "English" or "sewed-in" bag-frame which to all appearances is the same as any ordinary "English" or "sewed-in" bag-frame, but is provided with angle-irons or brackets of such 55 novel and simple construction, that a strong

bag-frame is produced, and that the machine-stitching or sewing of the leather bag to the frame is not interfered with; in other words, that the leather body-portions of a traveling bag, satchel, or other bag, are 60 readily sewed thereto by means of machine-stitching or sewing in one continuous operation from one end of the frame to the other end of the same, and that the usual hand-sewing or the blind-stitching over the angle-irons or brackets is avoided. 65

The invention has for its further object that, by the use of the bag-frame and angle-irons or brackets therefor embodying the principles of the present invention, "Eng- 70

75

lish" or "sewed-in" bags may be manufac- 80

<p

tion of the bag-frame and the novel angle-irons or brackets therefor, said view being made on a reduced scale; and Fig. 5 is a detail horizontal section, said section being taken on line 5—5 in said Fig. 4, looking in the direction of the arrow α , and said view being made on a slightly enlarged scale. Fig. 6 is a perspective view of one of the said angle-irons or brackets; and Fig. 7 is a similar view of a slightly modified form of angle-iron or bracket.

Similar characters of reference are employed in the above described views, to indicate corresponding parts.

15 In the said drawings, the reference-character 1 indicates an "English" or "sewed-in" bag, the leather bag-portions 2 of which are secured to the bag-frame 3 by means of the machine-stitching 4. As is usual in the construction of "English" or "sewed-in" bag-frames, the frame-portions or body-sections of the bag-frame are also leather-covered, as at 5, see Fig. 2 of the drawings. The bag-frame 3 comprises a pair of frame-sections 6 and 7. To the said frame-section 6 is secured, by means of the angle-irons or brackets to be presently more fully described, the side plate 8, and secured to the said frame or body-section 7, by means of the angle-irons 30 or brackets, also to be presently more fully described, is the side plate 9, said body sections and plates being made in the manner usual in the construction of bag-frames, and said plates 8 and 9 being pivotally connected 35 or hinged, as at 10, and as shown in Fig. 4 of the drawings.

As shown more particularly in Figs. 3 and 4 of the drawings, the angle-irons or brackets for connecting the side plate 8 with the frame or body section 6, so as to provide a sewing-space 11, and the angle-irons or brackets for connecting the side plate 9 with the frame or body-section 7, to provide a sewing-space 12, while differing in size, because of the fact that the one frame-section, in closing the bag-frame, must enter beneath the other frame-section, are both substantially the same in their general configuration and construction. Each angle-iron or bracket consists, essentially, of a main body-portion 13 having connected therewith and extending therefrom at an angle, near the lower end-portion of said body-portion 13, a rivet-lug 14. At its upper end, the said body-portion 13 is formed with a supporting arm 15, extending at an angle from said body-portion 13 and in alignment vertically with the rivet-lug 14. Upon its upper marginal surface-portion, and extending in an upward direction, is another rivet-lug 16. That part of the body-portion 13 where it joins onto the said supporting arm 15 has its opposite surface-ports chamfered, as at 17 and 18, see more particularly Fig. 6 of

the drawings, so that those portions of the angle-irons or brackets, which extend over the sewing-spaces 11 and 12 of the respective frame-sections are of the general cross-sectional configuration shown in Fig. 5 of the drawings, thus presenting to the reciprocating motions of the sewing needles, when stitching the leather bag to the frame, two sharp edges, as 19 and 20, which with the inclined surface-portion 17 and 18, should 75 the needles strike the angle-iron or bracket, will deflect the needles to one side of the angle-iron or bracket, without the least danger of breaking the sewing needles or otherwise, perhaps, damaging the leather bag or 80 the sewing machine. The manner of riveting the angle-irons or brackets to the respective members of the respective frame-sections of the bag-frame will be clearly understood from an inspection of Fig. 3 of the drawings, and need not be further described.

In Fig. 7 of the drawings, I have shown a slightly modified form of angle-iron or bracket which may be employed with substantially the same results as the said form 90 of angle-iron or bracket represented in said Figs. 3, 4, 5 and 6, and described hereinabove. The form of bracket represented in said Fig. 7 is made of wire, and is preferably, of circular cross-section, said bracket 95 comprising a main body 21, having a lower riveting end-portion 22. Extending from the upper end-portion of said body 21 is a supporting arm 23 formed at its free end with an angular riveting end-portion 24. 100 The manner of riveting this form of angle-iron or bracket to the respective members of the respective frame-sections of the bag-frame is similar to that described in connection with the form of angle-iron or bracket 105 represented in said Fig. 6 of the drawings, and will be clearly understood from an inspection of the view of the bracket illustrated in Fig. 7. As has been stated, the bag-frame sections are provided with coverings of leather or other analogous material, and the leather edge-portions surrounding the mouth of the bag-body being placed in position may be stitched or sewed in place, the sewing needles of the sewing machine 115 passing through the sewing spaces 11 and 12, and over the non-interfering angle-irons or brackets, thus providing a method of continuously stitching the bag to the frame, from end to end of the bag-frame.

Of course I am aware that some changes may be made in the general arrangement and constructions of the various parts comprising the frame for use with "English" or "sewed-in" bags, without departing from the scope of the present invention as set forth in the foregoing specification and as defined in the clauses of the claim which are appended thereto. Hence, I do not limit my present invention to the exact arrange- 120 125 130

ments and combinations of the various devices and parts as described in the said specification, nor do I confine myself to the exact details of the construction of the said parts as illustrated in the accompanying drawings.

I claim:

1. A jaw frame member for hand bags and the like comprising two flat members disposed transversely to each other and separated from each other by a free space, and brackets connecting said members with each other each spanning the open space and presenting a surface to said space adapted to deflect a needle striking the same.
2. An angle jaw-frame for hand bags and the like having its respective flanges separated by an open space, and connectors for rigidly securing said flanges to each other, said connectors spanning said open space and having surfaces opposing the same adapted to deflect a needle striking said connectors when sewing the bag body to said frame.
3. An "English" or "sewed-in" bag frame comprising upper and lower frame-sections and side-plates, angle-irons or brackets connected with the respective upper and lower frame-sections and the side-plates, so as to provide sewing-spaces between the said upper and lower frame-sections and the side-plates, said angle-irons or brackets being formed with inclined surfaces which provide needle-deflecting portions to deflect the needle, while sewing, into said sewing spaces to permit of continuous machine-stitching of a bag-body to said frame.
4. An "English" or "sewed-in" bag frame comprising upper and lower frame-sections and side-plates, angle-irons or brackets connected with the respective upper and lower frame-sections and the side-plates, so as to provide sewing-spaces between the said upper and lower frame-sections and the side-plates, said angle-irons or brackets being formed with inclined surface-portions and sharp edges, so as to provide needle-deflecting portions to permit of continuous machine-stitching of a bag-body to said frame.
5. An "English" or "sewed-in" bag frame comprising a pair of frame-sections and a side-plate connected with each frame-section, said side-plates being located vertically in alinement with and directly beneath and within the marginal edges of the respective frame-sections, angle-irons or brackets connected with the respective upper and lower frame-sections and the side-plates, so as to provide sewing spaces between the said upper and lower frame-sections and the side-plates, said angle-irons or brackets being formed with inclined surfaces which provide needle-deflecting portions to deflect the needle, while sewing, into said sewing spaces to permit of continuous machine-stitching of a bag-body to said frame.
6. An "English" or "sewed-in" bag-frame comprising a pair of frame-sections and a side-plate connected with each frame-section, said side-plates being located vertically in alinement with and directly beneath and within the marginal edges of the respective frame-sections, angle-irons or brackets connected with the respective upper and lower frame-sections and the side-plates, so as to provide sewing spaces between the said upper and lower frame-sections and the side-plates, said angle-irons or brackets being formed with inclined surface-portions and sharp edges, so as to provide needle-deflecting portions to permit of continuous machine-stitching of a bag-body to said frame.
7. A bag-frame section comprising a main body-section and a side-plate, said side plate being located in a plane at right angles to the plane of the body-section and beneath and within one of the marginal edges of the body-section, angle-irons or brackets connected with said body-section and said side-plate, so as to provide a sewing space between said body-section and the side plate, said angle-irons or brackets being formed with inclined surfaces which provide needle-deflecting portions to deflect the needle, while sewing, into said sewing spaces to permit machine stitching continuously from one end of the bag-frame to the other end thereof.
8. A bag-frame section comprising a main body-section and a side-plate, said side plate being located in a plane at right angles to the plane of the body-section and beneath and within one of the marginal edges of the body-section, angle-irons or brackets connected with said body-section and said side-plate, so as to provide a sewing space between said body-section and the side plate, said angle-irons or brackets being formed with inclined surface-portions and sharp edges, so as to provide needle-deflecting portions to permit machine-stitching continuously from one end of the bag-frame to the other end thereof.
9. A bag-frame section comprising a main body-section and a side-plate, and angle-irons or brackets, each angle-iron or bracket comprising a main body-portion, a supporting arm extending at an angle from said body-portion, and means for securing said body-portion and said arm to said side-plate and the body-section of the bag-frame, and the body-portion of the bracket or angle-iron being formed with inclined surfaces which provide needle-deflecting portions to deflect the needle, while sewing, into said sewing spaces to permit machine-stitching continuously from one end of the bag-frame to the other end thereof.

10. A bag-frame section comprising a main body-section and a side-plate, and angle-irons or brackets, each angle-iron or bracket comprising a main body-portion, a supporting arm extending at an angle from said body-portion, and means for securing said body-portion and said arm to said side-plate and the body-section of the bag-frame, and the body-portion of the bracket or angle-iron being formed with inclined surface-portions and sharp edges, so as to provide needle-deflecting portions to permit machine-stitching continuously from one end of the bag-frame to the other end thereof.
11. A bag-frame section comprising a main body-section and a side-plate, and angle-irons or brackets, each angle-iron or bracket comprising a main body-portion, a supporting arm extending at an angle from said body-portion, and rivet-lugs connected with and extending from said body-portion and said arm for securing said body-portion and said arm to said side-plate and the body-section of the bag-frame, and the body-portion of the bracket or angle-iron being formed with inclined surfaces which provide needle-deflecting portions to deflect the needle, while sewing, into said sewing spaces to permit machine-stitching continuously from one end of the bag-frame to the other end thereof.
12. A bag-frame section comprising a main body-section and a side-plate, and angle-irons or brackets, each angle-iron or bracket comprising a main body-portion, a supporting arm extending at an angle from said body-portion, and rivet-lugs connected with and extending from said body-portion and said arm for securing said body-portion and said arm to said side-plate and the body-section of the bag-frame, and the body-portion of the bracket or angle-iron being formed with inclined surface-portions and sharp edges, so as to provide needle-deflecting portions to permit machine-stitching continuously from one end of the bag-frame to the other end thereof.

In testimony, that I claim the invention set forth above I have hereunto set my hand this 6th day of February, 1914,

HUGO TUECKMANTEL.
